United States Patent Office.

ALFRED L. SEABURY AND DAVIDSON MORRIS, OF NORFOLK, VIRGINIA.

Letters Patent No. 96,273, dated October 26, 1869.

IMPROVED BLIND-HINGE.

The Schedule referred to in these Letters Patent and making part of the same.

To all whom it may concern:

Be it known that we, ALFRED L. SEABURY and DAVIDSON MORRIS, of Norfolk, in the county of Norfolk, and State of Virginia, have invented a new and useful Improved Hinge and Catch; and we do hereby declare that the following is a full, clear, and exact description thereof, reference being had to the accompanying drawing, in which—

Figure 1 is an elevation of the inner edge of a window-frame, and two shutter-hinges secured thereto; and

Figure 2, a transverse section, taken in the line x , of fig. 1, looking down on to the lower hinge.

Like letters designate like parts in all the figures.

The nature of our invention consists in connecting the upper and lower hinges of window-shutters by means of a rod, when said hinges are used for securing or locking the shutter in any desired position.

To enable those skilled in the art to make and use our invention, we will proceed to describe its construction and operation.

In the drawing, the upper and lower hinges are of different form, the upper one being intended for heavier shutters than the lower one. In the upper one, the upper half of the hinge is represented as being raised, to show the pivot upon which it turns.

A represents the portion of the hinge which is secured to the window-frame, and B the portion which is secured to the shutter.

Each of them has circular flanges, a b .

In the centre of the lower one is a pivot, c , upon which the upper one turns.

Pivoted to the outer side of the parts A A are two levers, C C, the inner ends of which are connected together by means of a rod, D.

In the flanges b b are notches, d , into which the outer ends of the levers C C fit when it is desired to hold the shutters in any fixed position.

In the drawing, the hinge is represented as it would be when the shutter is open or thrown back against the wall.

When it is desired to close the shutter, by raising the rod D the outer ends of the levers C C will be lowered and released from the notches in the flanges b b , which will allow the shutter to turn freely.

When it is closed, the notches next to the shutter will be over the outer ends of the levers C C, when, by drawing down the rod D, the said levers will resume their former positions, thereby again locking the hinges.

Having thus fully described our invention,

What we claim, and desire to secure by Letters Patent, is—

Connecting the upper and lower hinges of shutters, when the hinges are used for holding the shutters in any desired position, by means of a rod, or its equivalent, substantially as shown and described.

ALFRED L. SEABURY.
DAVIDSON MORRIS.
